SEPARATION OF ORGANIC NITROGEN COMPOUNDS FROM ADMIXTURE WITH HYDROCARBONS

Raymond N. Fleck, Whittier, and Carlyle G. Wight, Fullerton, Calif., assignors to Union Oil Company of California, Los Angeles, Calif., a corporation of California

Application November 26, 1956, Serial No. 624,238

17 Claims. (Cl. 208—254)

This invention relates to the refining of hydrocarbons, particularly those contaminated with organic nitrogen compounds. Such hydrocarbons include those which are produced as petroleum, such as coal tar oil fractions and shale oils among others.

Many crude petroleum streams are found to contain in addition to the principal hydrocarbon constituents considerable quantities of organic nitrogen compounds. In some cases the incidence of these nitrogen compounds is sufficient that the nitrogen content runs as high as 1.0% by weight. California crude oils in many cases average 0.5% by weight of nitrogen. Mexican and Venezuelan crudes have nitrogen contents ranging from about 0.2% to about 0.35% by weight. Extensive analyses of these nitrogen-containing crudes indicate that much of the nitrogen occurs in the form of amines or the so-called nitrogen bases. These include pyridine, quinoline, and the mono, di, tri, and tetra alkylated derivatives of these materials. For example in California kerosene distillate the di, tri, and tetra alkylated quinolines and certain polyalkylated pyridines are found. There is however considerable nonbasic nitrogen present in these materials. Coal tar oils produced in the coking of coal, contain extensive quantities of nitrogen bases and these are principally aromatic amines and heterocyclic nitrogen compounds. Shale oil produced by the heating and retorting of shale rock, such as that which is found in Colorado and elsewhere, resembles waxy crude but is characterized particularly in that it contains such extensive quantities of organic nitrogen compounds that the nitrogen content runs as high as about 2.5% by weight.

Crude petroleum, coal tar oils, and shale oils are principal or potential sources of liquid fuels and solvents. The presence of nitrogen compounds in the fuel or solvent product imparts a very bad odor to these materials. Their presence in the original oil very adversely affects hydrocarbon refining techniques by which the fuels and solvents or other materials are produced. They have, for example, a well defined adverse effect on such processes as catalytic cracking, catalytic isomerization, and catalytic reforming, particularly platinum catalyzed reforming. The nitrogen compounds appear to be adsorbed on the catalyst and selectively deactivate its active cracking centers. In catalytic cracking, for example, the gasoline yield may be reduced as much as 50% through the presence of sufficient organic nitrogen compounds to give the feed a nitrogen content of about 0.3% by weight and reduced by 75% when the nitrogen content reaches about 0.45%. Platinum catalyzed reforming and other reforming processes in general are also adversely effected by nitrogen compounds in the feed. With halide promoted platinum catalysts the nitrogen compounds appear to react with the catalyst forming ammonium halides which deposit in the apparatus. This deactivates the catalyst and lowers the yield unless the halide is replenished continuously.

Because of the adverse effects, repeated attempts have been made to remove the nitrogen compounds from hy-

2

drocarbon feed-stocks in refining processes and from the products produced. For example, acid treating with dilute sulfuric acid forms water soluble salts with the basic nitrogen compounds, i.e. the nitrogen bases, or the amines. It is otherwise ineffective with respect to the nonbasic nitrogen compounds. Catalytic hydrogenation is effective to remove most all of the nitrogen compounds, but in order to reduce their incidence in the hydrogenated product to a level which does not adversely effect a platinum catalyzed reforming process for gasoline, hydrogenation pressures of the order of 5,000 p.s.i. and higher are required. Treatment of such materials with fuller's earth tends to reduce the quantity of nitrogen compounds, but this involves a relatively high liquid yield loss through retention of hydrocarbons on the adsorbent and the nitrogen compounds are lost through disposal of the spent adsorbent. Further, it is seldom if ever possible in this way to reduce the nitrogen contamination sufficiently to avoid platinum catalyst poisoning.

20 The present invention is directed to a highly efficient and improved process for removing all and recovering most of the basic and nonbasic nitrogen compounds from petroleum, coal tar, and shale oil crudes, distillates and other fractions.

25 It is a primary object of this invention to provide an improved process for the denitrogenation of hydrocarbons which are contaminated with organic nitrogen compounds.

30 It is a more specific object of this invention to process hydrocarbon streams contaminated with organic nitrogen compounds by distilling the feed to produce a plurality of fractions, contacting a specific solid contact material with the feed fractions in a sequence to produce a series of effluents having hydrocarbons freed of the nitrogen compounds originally present but now mixed with nitrogen compounds from a different feed fraction, and distilling each effluent to separate the nitrogen compounds from the hydrocarbons of different boiling range.

35 It is a specific object to provide a process according to the foregoing object in which the feed is distilled into two portions which alternately contact the contact material.

40 It is a further object to provide in such a process for distilling the feed fraction into a plurality of more than two fractions and in which the solid contact material is contacted with these fractions in a sequence of increasing average boiling point.

45 It is another object to provide in such a process for the distillation of such feed streams into a plurality of fractions and contacting the even numbered fractions with one mass of contact material while contacting the odd numbered fractions with a separate mass of contact material, each of the contacts being in a sequence of increasing average boiling point.

50 It is also an object to include in the foregoing process the step of regenerating the contact material and freeing it of heavy organic nitrogen compounds by combustion thereof in the presence of an oxygen-containing gas.

55 Other objects and advantages of the present invention will become apparent to those skilled in the art as the description and illustration thereof proceed.

60 Briefly the present invention comprises an improved denitrogenation process for treating one or more hydrocarbon streams derived from virtually any source and which are contaminated with organic nitrogen compounds. The process consists of a combination of fractionation and solids-fluid contact steps. In the latter step a granular solid contact material is contacted in sequence with a plurality of selected feed hydrocarbon streams, or with the various portions of a single feed stream in a specific order. This produces effluents which upon refractionation are much more readily freed of the or-

ganic nitrogen compounds present therein. The granular solid contacting step employs a solid zeolitic metallo alumino silicate contact material, more precisely defined and described below, which has an extremely high affinity for nitrogen compounds of the type occurring in hydrocarbon streams. In combination with this contacting step the process utilizes a plurality of individual hydrocarbon streams or a preliminary fractionation step in which a single wide boiling range feed stream is divided into a plurality of fractions of relatively narrow boiling range. These individual streams are passed through contact with the solid material in a sequence. The individual effluents from the solid contact step are again fractionated to separate nitrogen compounds originating in one of the feed streams from hydrocarbons originating in another of the feed streams, which fraction had a different average boiling point or is otherwise readily separable from the first stream. The nitrogen compounds after treatment with the solid material are thus readily distillable from the hydrocarbons present in that particular effluent.

The present invention will be described in connection with the denitrogenation of various petroleum and shale oil fractions. In the case of the shale oil fractions, the nitrogen analysis is ordinarily very high and they present some of the most difficult hydrocarbon streams to denitrogenate. The process is however also applicable to other hydrocarbon streams similarly contaminated including those derived from petroleum, coal and other sources.

The feed mixture is distilled into a plurality of at least two fractions. In the simplest modification of this process, there are two of such fractions. The granular solid metallo alumino silicate is contacted first with the lower boiling fraction, whereby the nitrogen compounds are preferentially adsorbed leaving the contact material saturated therewith while the hydrocarbon constituents are substantially unadsorbed. Instead of heating the spent contact material and stripping it with a fluid such as steam or other material, the spent solids in this process are next contacted with the higher boiling feed fraction. The nitrogen compounds present therein effect an extremely active and rapid displacement exchange with the lower boiling nitrogen compounds on the spent solid material and which originated in the lower boiling feed fraction. The higher boiling organic nitrogen compounds thus accumulate on the solids while the lower boiling nitrogen compounds are liberated in the displacement exchange. This second effluent stream comprises the higher boiling hydrocarbons in admixture with the displaced lower boiling nitrogen compounds. These are readily distillable in most cases from one another.

The thus treated contact material, now saturated with the higher boiling organic nitrogen compounds, is again contacted at approximately the same temperature with the lower boiling fractions of the feed stream. A reverse displacement exchange is effected in which the lower boiling nitrogen compounds displace the higher boiling nitrogen compounds present on the solids. This produces a first effluent stream comprising the lower boiling hydrocarbons, which are unaffected by the solids, and the higher boiling nitrogen compounds displaced from the solids. This effluent is also readily distillable to separate the lower boiling from the higher boiling materials.

The aforementioned, distillations are effected separately and each produces an overhead and a bottoms product. In the case of the first effluent stream the overhead product comprises the lower boiling hydrocarbons substantially free of nitrogen compounds while the bottoms fraction comprises the high boiling nitrogen compounds substantially free of hydrocarbons. In the distillation of the second effluent stream, the overhead product comprises the lower boiling nitrogen compounds and the bottoms product comprises the higher boiling hydrocarbons.

It is within the contemplation of this invention as applied to fairly wide boiling range feedstocks to subdivide the feed material into a plurality of more than two fractions and to contact fractions the specific granular solid contact material herein preferred in a sequence whereby similar displacement exchange phenomena occur to produce a plurality of effluents which are distilled as previously indicated. The sequence preferred is that of increasing average boiling point. If desired, the solid contact material may be regenerated by oxidation after the contact with the highest boiling feed fraction in order that the heaviest and most difficultly removable nitrogen compounds may be removed. Such a regeneration is also applicable to the process in which only two feed fractions are employed in order to regenerate the granular solids periodically. Even in the case of a relatively narrow boiling range feed material, particularly one which has a relatively high average boiling point, a single contact with the preferred solids to remove the nitrogen compounds from the hydrocarbons is effectively followed by a regeneration with an oxygen-containing gas to burn off the nitrogen compounds.

The contact material employed in the process of this invention is a solid granular adsorbent having a mesh size range between about 2 and 100 mesh or finer and preferably between about 4 and about 30 mesh in static and moving bed contacts. It is used in the form of a dense compact bed of material through which the feed and displacement and exchange recycle streams pass, either in the vapor phase or in the liquid phase. The process may employ the adsorbent in the form of a single static bed of material in which case the process is only semi-continuous. Preferably a plurality of two or more static beds of adsorbent are employed with appropriate remotely operable valving so that the feed stream is passed through one or more of the adsorbents in a set while the exchange displacement stream passes through one or more of the other adsorbents in the set. In this case the feed and product flows are continuous, in either the vapor or liquid phase, and either up or down through the adsorbent. When the granular material is sufficiently rugged physically the moving solids bed modification may be employed in which flow of feed is maintained continuously through an adsorption zone, the flow of displacement exchange fluid is maintained continuously through a desorption zone, and the granular adsorbent is recirculated successively through these two zones. With the smaller sized mesh ranges of adsorbent, the material may be fluidized in and by the fluid streams contacting it, although the compact bed modifications are preferred since a greater number of theoretical and actual contact stages are more readily obtained in smaller and simpler equipment.

The present invention may not be carried out with most of the commonly available solid granular adsorbents. It has been found that the particular solid materials which are more efficient the hydrocarbon denitrogenation process of the present invention are the natural or synthetic crystalline partially dehydrated metallo alumino silicates. These materials must have pore sizes exceeding a minimum of 7 Å. in diameter in order for the nitrogen compounds to be preferentially separated from the hydrocarbons. The average composition of one typical synthetic zeolite having a pore size of about 13 Å. is $5\text{Na}_2\text{O} \cdot 6\text{Al}_2\text{O}_3 \cdot 15\text{SiO}_2$. It may be prepared by heating stoichiometric quantities of alumina and silica and excess caustic under pressure. The excess is washed out and if desired other desired metal ions may then be introduced by ion exchange. Part of the sodium in this material can be ion exchanged with concentrated salt solutions at superatmospheric pressure and temperatures of 150-300 °C. to introduce other metal ions.

The synthetic crystalline partially dehydrated metallo alumino silicate zeolitic adsorbents are presently available items of commerce marketed by Linde Air Products Com-

pany, 30 E. 42nd Street, New York 17, New York, under the name of "Molecular Sieves 10X, 13X, etc." and these have pore diameters of 10 Å. and 13 Å. respectively.

In the process of this invention the solid adsorbent utilized for the hydrocarbon denitrogenation appears to be deactivated only very slowly. Ultimately in a long continued process then the material may require regeneration due to the accumulation on the material of traces of very high molecular weight hydrocarbonaceous materials present in the feed stream. Since the temperature at which the feed contact and the displacement exchange contact are carried out is relatively low, little if any chemical reaction ordinarily occurs in contact with the material. The accumulated deactivating materials may be removed from the metallo alumino silicate adsorbent by heating to temperatures of the order of those customarily employed in the oxidative regeneration of spent hydrocarbon conversion catalysts and passing a dilute oxygen-containing stream in contact therewith. Regeneration may also be effected by stripping with steam followed by contact at this temperature with an anhydrous gas.

The process of this invention and the various modifications and applications thereof, as well as several forms of the apparatus in which the process may be effected, will be more readily understood by reference to the accompanying drawings in which:

Figure 1 is a schematic flow diagram of the denitrogenation process of this invention in which the feed stream is distilled into two fractions which alternately contact the zeolitic adsorbent followed by distillation of the first and second effluents,

Figure 2 is a schematic flow diagram of the process of Figure 1 modified to employ a recirculating stream of the adsorbent in the form of a downwardly moving dense solids bed,

Figure 3 is a similar modification of this process as shown in Figure 2 in which a plurality of four feed streams is employed and in which the spent adsorbent saturated with the heaviest nitrogen compounds is regenerated by burning them from the solids with an oxygen-containing gas, and

Figure 4 is a modification of the process shown in Figure 3 in which two downwardly moving beds of adsorbent are employed, one of which contacts in sequence of increasing average boiling point the even numbered feed fractions and the other of which contacts the odd numbered feed fractions.

Referring now more particularly to Figure 1, the essential elements of this modification of the process include feed distillation column 10, first and second contacting vessels 12 and 14 each containing a static bed of the metallo alumino silicate adsorbent having approximately 10 Å. pores, four-way control valves 16 and 18 operated remotely by cycle timer operator 20 and first and second effluent distillation columns 22 and 24 for treating the first and second effluents respectively. For sake of simplicity of illustration and explanation, the conventional pumps, valves, heaters and coolers, overhead condensers, and bottoms reboilers which are conventionally employed in such systems have been eliminated from the drawings. Their use however is well known to those skilled in the art and conventional.

In the process of Figure 1, a feed stream which for purposes of example is 1,000 barrels per day of a shale oil gasoline fraction boiling between about 120° F. and 400° F. and contaminated with organic nitrogen compounds to the extent that it analyzes about 2.5% by weight nitrogen. This feed is introduced through line 26 at a rate controlled by valve 28 into feed still 10. The feed is separated into 700 barrels per day of an overhead distillate boiling between about 120° F. and 300° F., which is removed from still 10 through line 30, and 300 barrels per day of a bottom fraction boiling between about

300° F. and 400° F. which is removed from still 10 through line 32.

The cut point between feed fractions (300° F. here) is preferably determined by the rate of displacement exchange of the nitrogen compounds in each stream. In each instance the cut point is determined so that with a given quantity of the adsorbent the nitrogen compounds in each feed fraction will exchange with and displace the nitrogen compounds from the adsorbent which accumulates from the other feed in about equal periods of time. For example in this case the 120° F. to 300° F. light fraction and the 300° F. to 400° F. heavy fraction simultaneously contact individual static beds of the 10 Å. adsorbent and periodically the contact is reversed. The 300° F. cut point here is determined so that the nitrogen compounds in the light fraction flowing at 700 barrels per day will displace and exchange the heavy nitrogen components from one bed of adsorbent in the same period of time that the nitrogen compounds in the heavy fraction flowing at 300 barrels per day will displace and exchange the light nitrogen compounds from the other bed of adsorbent. The displacement exchange of low boiling nitrogen compounds from the adsorbent by higher boiling compounds in the vapor phase is faster and more efficient than the reverse step, and so in general the lower boiling fractions have the larger flow rates. But this is also affected by the concentration distribution of the nitrogen compounds in the full boiling range material, and the cut point or points thus must be determined experimentally or by careful calculation from the nitrogen analysis of various fractions. In any event, the cut point is determined so that in each contacting step saturation of the adsorbent would ultimately occur in each stage at the same time.

Another but less efficient way of controlling this is to determine the cut point independently of the above considerations, and recirculate a stream of nitrogen compounds into the feed fraction having a relative deficiency, i.e., that one having a nitrogen compound concentration less than equivalent to the other stream or streams on a time basis.

Where individual feed streams are treated, the nitrogen equivalence on a time basis is readily maintained by controlling the flow rates of the streams at different values so that nitrogen break-through would occur simultaneously.

The four-way control valves 16 and 18 operated by cycle timer operator 20 alternately feed the overhead distillate and the bottoms product through each of contacting vessels 10 and 12. At the beginning of each contact with one feed fraction, the 10 Å. adsorbent is saturated with nitrogen compounds of the other fraction. Thus in contacting vessel 12 the overhead distillate flows in the vapor phase through line 30 and control valve 18 through line 34 downwardly through first contacting vessel 12. The lower boiling nitrogen compounds are retained by the adsorbent displacing the higher boiling nitrogen compounds originating in the other feed fraction, and the lower boiling hydrocarbon components pass through unaffected. A first effluent is removed through line 36 and contains the lower boiling hydrocarbons and the nitrogen compounds of the higher boiling feed. This material flows through control valve 16 and line 38 into first effluent still 22. Herein the lower boiling hydrocarbon stream boiling between about 120° F. and 300° F. is produced as an overhead product through line 40. The bottoms product comprises the nitrogen compounds boiling between about 300° F. and 400° F. and this is produced through line 42.

At the same time the lower boiling fraction is contacting the 10 Å. adsorbent in first contacting vessel 12, the higher boiling fraction passing through line 32 and valve 16 flows through line 44 upwardly through second contacting vessel 14. The higher boiling nitrogen compounds are preferentially adsorbed by the adsorbent,

thereby displacing the lower boiling nitrogen compounds previously accumulated, and a second effluent is produced consisting of the 300° F. to 400° F. boiling range hydrocarbons and the 120° F. to 300° F. boiling range nitrogen compounds displaced from the adsorbent. This second effluent flows on through line 46, valve 18, and line 48 into second effluent still 24. The overhead product produced through line 50 from this still comprises the 120° F. to 300° F. boiling range nitrogen compounds and the bottoms product produced through line 52 comprises the 300° F. to 400° F. boiling range hydrocarbons. In Figure 1 the two streams flowing through lines 42 and 50 and containing the light and heavy nitrogen compounds are shown as being combined to produce a single nitrogen compound rich stream flowing through line 54 to production or storage facilities not shown. If desired however, these two streams may be produced separately. The same is true of the combined hydrocarbon streams shown produced through line 56.

In the process of the foregoing example, the contacting temperature employed in zones 12 and 14 is about 410° F. so that each stream is in the vapor phase. With wider boiling range materials such as those boiling between about 600° F. to 700° F. and higher, this constant adsorption temperature characterizing the process of this invention may be effected at temperatures below the normal boiling point of the highest fractions by passing these streams at reduced pressures in contact with the adsorbent. For example, a wide boiling range shale oil coker distillate boiling between about 120° F. and 600° F. is readily processed according to the process of this invention at about 403° F. The feed stream is distilled into three fractions. The first fraction boils between about 120° F. and 400° F. and is contacted with a 13 A. adsorbent at 403° F. in the vapor phase under normal atmospheric pressure. The second fraction boils between about 400° F. and 500° F. and is contacted in the vapor phase at the same temperature at an absolute pressure of 0.285 atmosphere. The third fraction boiling between about 500° F. and 600° F. is contacted at this same temperature at a pressure of 0.047 atmosphere.

Referring now more particularly to Figure 2, a modification of the process shown in Figure 1 is illustrated employing the same feed still 10, first effluent still 22, second effluent still 24, but in which the static beds of 13 A. adsorbent employed in vessels 12 and 14 have been replaced with a recirculated downwardly moving bed of the same material maintained in contacting column 60. The feed stream is again introduced through line 26 and valve 28 into feed still 10 which produces a light overhead distillate fraction through line 30 and a heavier bottoms product through line 32. The first effluent is again passed through line 34 into first effluent still 22 and produces the light hydrocarbon fraction through line 40 and heavy nitrogen compounds through line 42. The second effluent stream is again passed through line 48 into second effluent still 24 which produces the light nitrogen compounds as an overhead product through line 50 and the heavy hydrocarbons as a bottoms product through line 52.

The modification here lies in contacting column 60 in which the 13 A. granular solid adsorbent is recirculated through column 60 by means of any form of suitable conveyor 62. The solid material is introduced at the top of the column 60, and is removed from the bottom of the column after passing downwardly successively through first seal stream disengaging zone 64, first effluent disengaging zone 66, first contacting zone 68, first light feed engaging zone 70, second sealing zone 72 including second sealing gas engaging zone 74, second effluent disengaging zone 76, second contacting zone 78 and second feed fraction engaging zone 80.

The first feed fraction flows through line 30 upwardly through first contacting zone 68 in which the light nitrogen compounds are retained by and the heavy nitrogen

compounds are displaced from the 13 A. adsorbent into admixture with the unaffected light hydrocarbons to produce the first effluent flowing through line 38. The solids now saturated with light nitrogen compounds move downwardly into and through second contacting zone 78. Here they are contacted by the heavy or second feed fraction. The heavy nitrogen compounds preferentially displace and are exchanged for the light nitrogen compounds, thereby producing the second effluent comprising a mixture of the heavy hydrocarbons unaffected by the solids and the displaced light nitrogen compounds. These two streams are distilled individually as in the process illustrated in Figure 1. The solid adsorbent removed from the bottom of the column is saturated with heavy nitrogen compounds. Such saturated adsorbent is delivered into first contacting zone 68 in which the heavy nitrogen compounds are displaced in exchange for the light nitrogen compounds in the first or light feed fraction.

In order to prevent contamination of the first and second effluent streams, a first seal stream is removed from disengaging zone 64 and pumped by means 82 through line 84 and valve 86 into first feed fraction engaging zone 70. Similarly a second seal stream is pumped by means 88 from second disengaging zone 74 through line 90 into this same engaging zone.

Referring now more particularly to Figure 3, a somewhat more complex modification of the present invention is shown in which a relatively wide boiling range feed stream of hydrocarbons contaminated with organic nitrogen compounds is introduced through line 100 at a rate controlled by valve 102 into feed still 104. Herein the wide boiling range hydrocarbons are distilled into a plurality of four fractions. The first and lowest boiling range fraction is produced as an overhead distillate through line 106. The second or next higher boiling fraction is passed through line 108 into first side stripper 110 in which components desired in the overhead fraction are stripped therefrom and returned in the vapor phase to column 104 through line 112. The thus stripped next heavier feed fraction is removed from stripper 112 through line 114. The third or next to the highest boiling feed fraction is prepared from a stream flowing through line 116 from column 106 into second side stripper 118. Here components desired in the third feed fraction are freed from components desired in the fourth or highest boiling feed fraction in second side stripper 118. The heaviest components so separated are returned to column 106 through line 120 while the third feed fraction is produced through line 122. The fourth feed fraction is removed from the bottom of still 106 through line 124.

These four feed fractions may, if desired, be processed in the manner of Figure 1 modified to the extent that four static solids contacting vessels are provided through each of which the four feed streams are passed in a sequence of increasing average boiling point. After contact of each 13 A. adsorbent bed with the fourth feed fraction, the heaviest nitrogen compounds retained are burned off through contact with an oxygen-containing gas at temperatures of the order of 700° F. to 1200° F.

In the modification shown in Figure 3 however, this same sequence of solids-feed fraction contact is effected employing a single contacting vessel through which the 13 A. adsorbent is recirculated and passed downwardly as a moving bed. Contacting column 126 is provided with solids conveyor 127 which removes the granular adsorbent from the bottom of the column and reintroduces it at the top. The column is provided at successively lower levels with first contacting zone 128, second contacting zone 130, third contacting zone 132, fourth contacting zone 140, and solids regeneration zone 142. Through regeneration zone 142 is recirculated a gas stream comprising essentially flue gas by means of blower 144. This gas is passed through cooler 146 to

dissipate the liberated heat of regeneration and is returned through line 148 with additional oxygen-containing gas such as air introduced through line 150. The net production of flue gas is vented through line 152.

The first feed fraction passes upwardly countercurrent to the downwardly moving regenerated solids in first contacting zone 128. The lightest or first fraction nitrogen compounds are adsorbed leaving the first fraction hydrocarbons. This stream is produced substantially nitrogen-free as a first effluent stream through line 154.

The second feed fraction passes upwardly through second contacting zone 130. The second fraction nitrogen compounds are adsorbed displacing the first fraction nitrogen compounds into admixture with the second fraction hydrocarbons forming the second effluent stream removed through line 156. This material is distilled in second effluent still 158 to produce the first fraction nitrogen compounds through line 160 as an overhead distillate and the second fraction hydrocarbons as a bottoms product through line 162.

The third feed fraction introduced through line 122 passes upwardly countercurrent to the moving solids bed in third zone 132. The third fraction nitrogen compounds in this fraction displace the second fraction nitrogen compounds. This produces the third effluent comprising a mixture of the hydrocarbons from the third feed fraction and the nitrogen compounds from the second feed fraction. This effluent is produced through line 162 and is introduced into third effluent still 164. The second fraction nitrogen compounds are produced as an overhead fraction therefrom through line 166, and the third fraction hydrocarbon constituents are produced as a bottoms product through line 168.

The heaviest or fourth feed fraction introduced through line 124 passes upwardly countercurrent to the downwardly moving solids bed in fourth contacting zone 140. The nitrogen compounds from the fourth feed fraction are retained by the adsorbent and effectively displace the nitrogen compounds therefrom which originated in the third feed fraction. The fourth effluent flowing through line 170 comprises the hydrocarbons from the fourth feed fraction in admixture with the nitrogen compounds from the third feed fraction. This material is distilled in fourth effluent still 172 producing the third feed fraction nitrogen compounds as an overhead distillate through line 174 and the fourth feed fraction hydrocarbons as a bottoms product through line 176.

The three individual nitrogen compound fractions and the four individual hydrocarbon fractions may be produced separately if desired. They may be combined as indicated in Figure 3 in which case the nitrogen compounds from all but the fourth feed fraction are sent through line 178 to storage or further processing facilities not shown. The four hydrocarbon fractions may be similarly treated after passage through line 180.

In contacting column 126 somewhat different steps are taken in order to prevent intermixing of the feed fractions through flow between contacting zones. In this system a seal fluid distributor is provided above first contacting zone 128, below lowermost contacting zone 140, between the individual contacting zones in column 126, and at the bottom of regeneration zone 142. These engaging zones are essentially identical and indicated by numeral 182, followed by an appropriate letter distinguishing one from the other. A seal fluid inlet line 184 opens into each of these engaging zones. Preferably the seal fluid comprises an inert material which is readily separable from the effluent fluids. For hydrocarbon contact in the vapor phase a suitable seal fluid may comprise methane, ethane, propane, mixtures thereof, natural gas, carbon dioxide, nitrogen, carbon monoxide, hydrogen, and the like. The operating pressures of the various contacting zones are controlled in conventional ways so that the seal fluid so introduced splits and passes into

the superjacent and subjacent zones between which it is introduced. When the contact is conducted in the liquid phase, the seal fluid is appropriately a liquid which is also inert and which is readily separable from the effluents.

The spent granular adsorbent flowing from the bottom of fourth contacting zone 140 passes into solids regeneration zone 142 wherein the heaviest nitrogen compounds are burned from the solid material. The regenerated solids are returned as described for repassage through column 126. With a feed material comprising a shale oil coker distillate analyzing about 0.22% by weight nitrogen boiling between about 120° F. and 500° F., the four feed fractions have boiling ranges respectively of from 120° F. to 250° F., 250° F. to 325° F., 325° F. to 400° F., and 400° F. to 500° F. The downwardly moving adsorbent comprises the metallo alumino silicate having 13 Å. pores. The first effluent produced directly from the top of column 126 comprises a light gasoline analyzing about 0.002% nitrogen. The bottoms products from each of the three effluent distillation columns comprise the successively higher hydrocarbon constituents of the feed fractions and these analyze respectively 0.004, 0.005, and 0.007% nitrogen.

If desired, a 10 Å. adsorbent can be substituted for the 13 Å. used in the above example. In certain cases it is desirable to enhance the difference between the boiling range of the nitrogen compounds derived from one feed fraction and the boiling range of the hydrocarbon stream in which these materials are mixed when they are recovered from the solid contact material. For example, in the process of Figure 3, the nitrogen compounds whose boiling points lie between 120° F. and 250° F. are produced in the second effluent with hydrocarbons boiling between 250° F. and 325° F. In some cases nitrogen compounds boiling slightly below 250° F. are difficultly separable from hydrocarbons boiling slightly above 250° F. This problem depends upon the incidence of various types of nitrogen compounds and their normal boiling points. When such distillation problems occur, it is desirable to provide a "gap" or substantial difference between boiling ranges of fractions contacting the solids in succession and the process described in connection with Figure 4 provides an effective solution.

In Figure 4, four feed fractions are prepared in a manner identical to that described in connection with Figure 3 and are fed to the system. The lines through which corresponding feed fractions are introduced are indicated with the same numbers as those in Figure 3. Specifically, the first or lowest boiling feed fraction is introduced through line 106, the second or next heavier fraction is introduced through line 114, the third or next to the heaviest feed fraction is introduced through line 122, and the fourth or heaviest feed fraction flows through line 124.

In this modification, there is provided a first contacting column 200 provided with separate solids inlet 202 and a second contacting column 204 with solids inlet 206. Again the granular adsorbent moves downwardly as a moving bed through each contacting column, is removed respectively through lines 208 and 210, and is combined for regeneration in regeneration zone 212. The system for regeneration employed in this modification is identical to that shown and described in Figure 3.

A suitable conveyor 214 for the regenerated solids is provided to return these solids to the top of each of columns 202 and 204.

In this modification, two downward streams of adsorbent are used. The sequence of feed mixture contact comprises a series in which the end point of one mixture is substantially below the initial boiling point of the next mixture. For example, alternate feed fractions, in Figure 4, are passed successively into contact with the downwardly moving bed of adsorbent in first contacting column 200, while the remaining feed fractions, namely

the even numbered ones, are similarly passed into contact with the adsorbent in second column 204. If desired, three streams of adsorbent may be used and in this case the first stream of adsorbent contacts the first and fourth fractions, the second stream contacts the second and fifth fractions, and the third stream contacts the third and sixth fractions. Proportionally more fractions may be used if desired. More than three streams of adsorbent may be used, although ordinarily the two shown in Figure 4 and hereinafter described are sufficient to obtain ready effluent fractionation.

In this manner the displacement exchange between the organic nitrogen compounds in a given feed fraction involves displacement of the nitrogen compounds originating in a feed fraction boiling considerably lower, the degree depending upon the individual system. In this way there is a very substantial boiling point difference between the highest boiling nitrogen compound displaced from the solid material and the lowest boiling nitrogen compound which displaces it. For example, with two adsorbent streams and alternate fraction contact, nitrogen compounds displaced from the adsorbent and having normal boiling points in the range of from 200° F. to 250° F. are displaced by nitrogen compounds whose normal boiling points lie for example between 300° F. and 350° F. Thus the distillation separation between the 200° F. to 250° F. nitrogen compounds from the 300° F. to 350° F. boiling point hydrocarbons in a given effluent stream is facilitated.

First contacting column 200 is provided with first contacting zone 213 and third contacting zone 215. Second contacting column 204 is provided with second contacting zone 218 and fourth contacting zone 220. It is to be understood that in the event the feed stream is distilled into more than four fractions such as for example 6, 8, 10, etc., proportionately increased numbers of contacting zones are provided in the first and second contacting columns, that is, 3, 4, or 5 contacting zones each. If three contacting columns are used, the first, fourth, and seventh are introduced into the first column, the second, fifth, and eighth pass into the second column, etc. Against, suitable seal fluids are introduced above and below each individual contacting zone to prevent interflow of fluids therebetween.

In first contacting column 200 the downwardly moving metallo alumino silicate adsorbents first contacts the first feed fraction boiling between 120° F. and 250° F. producing a first effluent flowing through line 222 and comprising only the hydrocarbon constituents boiling between 120° F. and 250° F. The adsorbent containing the first fraction nitrogen compounds is then contacted in third contacting zone 216 with the third feed fraction, namely that boiling between 325° F. and 400° F. The 325° F. to 400° F. hydrocarbon effluent containing the displaced 120° F. to 250° F. nitrogen compounds is removed through line 224 and is distilled in still 226. The distillation is exceedingly easy since the highest boiling nitrogen compound boils at or below 250° F. and the lowest boiling hydrocarbon compound boils at or above 325° F. The nitrogen compounds are produced as an overhead distillate through line 228 and the hydrocarbon constituents are produced as a bottoms product through line 230. The nitrogen compounds present in the third feed fraction which are retained by the solid adsorbent in the lowermost contacting zone 216, pass into regeneration zone 212 where they are burned from the solids.

The moving bed of adsorbent in second column 204 passes downwardly through zones 218 and 220 wherein it is contacted successively by the second feed fraction flowing through line 114 and the fourth feed fraction flowing through line 124. The second feed fraction, freed of its nitrogen compounds on the regenerated adsorbent, flows through line 232 as a product of the process. The second fraction nitrogen compounds with normal boiling points between 250° F. and 325° F. are carried by the adsorb-

ent downwardly into fourth contacting zone 220 where they are removed from the adsorbent in displacement exchange for and by the fourth fraction nitrogen compounds boiling between 400° F. and 500° F. These nitrogen compounds are ultimately carried with the adsorbent into the regenerator and burned. The displaced 250° F. to 325° F. nitrogen compounds and the 400° F. to 500° F. hydrocarbon effluent flow from fourth contacting zone 220 through line 234 into still 236. Here again the displaced nitrogen compounds boil well below the hydrocarbon fraction and are produced as an overhead product through line 238 while the hydrocarbon fraction is produced as a bottoms product through line 240. The two nitrogen compound streams may be produced separately or in combination as shown in Figure 4 through line 242. The same is true of the four individual hydrocarbon streams which may be produced in admixture with each other, if desired, through line 244.

In the present process for hydrocarbon denitrogenation with the specific zeolitic metallo alumino silicate adsorbents having pore diameters of 7 Å. or greater, it has been found that the organic nitrogen compounds are very strongly retained by the solid granular adsorbent even at temperatures as high as about 850° F. It is therefore not always necessary that the contact pressure be reduced in the case of hydrocarbon fractions boiling in the higher temperature ranges. The zeolitic adsorbent can be contacted at a temperature of 850° F. with gasoline derived from raw shale oil in the vapor phase and substantially all of the nitrogen compounds are successfully removed. The spent solid material is then contacted with a recirculated stream of flue gas containing small controlled amounts of air whereby the nitrogen compounds are burned at temperatures of the order of 950° F. and the activity of the adsorbent is restored. The nitrogen compounds, whether they are basic or nonbasic, are removed through treatment by the process of this invention to an extent of 99.5%. A substantially complete removal of all nitrogen compounds is thus realized.

In the processes described and illustrated in connection with Figures 3 and 4, the heaviest organic nitrogen compounds in a given series are lost by combustion when the spent contact material is regenerated. The material which is lost includes the nitrogen compounds present in the highest boiling feed fraction which is processed in a given contacting column. In Figure 3 the nitrogen compounds in the fourth feed fraction are thus lost while in Figure 4 the nitrogen compounds in the second and fourth feed fractions are lost. This procedure is probably the most practical method of operating in those instances where the hydrocarbon fraction of the effluent is the most important. If the nitrogen compounds are to be used in the preparation of solvents, synthetic chemicals, and the like and are thus worth saving, a further modification of the contacting systems shown in Figures 1 and 2 may be employed. In those systems the granular adsorbent is first contacted with one feed fraction, then with a higher boiling fraction and then with the first feed fraction to produce two effluents which are separately distilled or otherwise fractionated to produce separate hydrocarbon and nitrogen compound streams. It is within the contemplation of this invention to fractionate wide boiling range feed materials into a plurality of more than two fractions as indicated in Figures 3 and 4, to contact a static or moving bed of the herein defined adsorbent in sequence with these fractions. The sequence employed is one of an increasing average boiling point as indicated in the process described in Figure 3, but instead of regenerating by combustion, the spent adsorbent after contact with the heaviest feed fraction is again contacted by one or more of the intermediate fractions having lower average boiling points to produce additional effluents which are separately distilled. Finally the thus treated adsorbent is again contacted with the lightest feed fraction, and the process is repeated. In this situ-

75

tion, none of the nitrogen compounds are lost through combustion. The number of effluents produced is equal to the number of feed streams. Each effluent is separately distilled to produce the nitrogen compounds as overhead products in the case of those effluents produced by contacting the adsorbent with a heavier feed fraction that it had contacted immediately before, and as a bottoms product in the case of those effluents produced by contacting the adsorbent with a feed fraction of lower average boiling point than the immediately previous contact.

Although the previous description has involved the use of the granular solid adsorbent in the form of static beds and downwardly moving beds, it should be understood that the adsorbent may be contacted with the various feed streams and with the regeneration gases while suspended or fluidized according to the well known principles of those fluid-contacting processes.

Although distillation is described as the procedure for separating the light and heavy constituents from the various effluents produced in the process, and as the procedure for producing the various feed fractions in the first instance, it should be understood that other fraction methods may be substituted, e.g., solvent extraction, crystallization, azeotropic distillation, steam stripping, and other fractionation procedures, depending upon the nature of the hydrocarbons and the nitrogen compounds contaminating the same.

The process of this invention thus consists of an improved denitrogenation process for contaminated hydrocarbon mixtures employing the principles of solid adsorption and fluid fractionation in such a way so as to remove organic nitrogen compounds from the feed stream and whereby the ordinary heating and gas stripping or liquid washing steps customary in prior adsorption processes have been completely eliminated. The process of this invention may be operated under pressure or under vacuum, and the actual operating pressures are actually determined by the pressure at which the feed stream is available and its boiling range, and whether the material being treated is desirably in the vapor phase or the liquid phase. The proper operating pressure can be determined by those skilled in the art from known physical characteristics of the materials to be separated, namely, the bubble point and dew point of the hydrocarbon feed stream and the known way in which these change with pressure. The operating temperatures employed in the process of this invention are also determined by the physical characteristics of the feed stream and the operating pressure, and also whether a vapor phase or a liquid phase operation is desired. In the complex gasoline streams the operating temperature is largely determined by the dew point and the bubble point of the stream at a given operating pressure. For example, operating temperatures above the dew point will obviously be in the vapor phase while operating temperatures below the bubble point will be in the liquid phase. It is within the contemplation of the present invention to adsorb the feed stream at a temperature between its bubble point and its dew point so that mixed phase contacting will be maintained for some special streams. Obviously the feed contact may be in the vapor phase followed by recycle stream contact in the liquid phase, or vice versa, if desired.

A particular embodiment of the present invention has been hereinabove described in considerable detail by way of illustration. It should be understood that various other modifications and adaptations thereof may be made by those skilled in this particular art without departing from the spirit and scope of this invention as set forth in the appended claims.

We claim:

1. A process for denitrogenating two hydrocarbon mixtures, each of which contains normally incident organic nitrogen compounds, the organic nitrogen compounds contained in the first of said mixtures being different from

the organic nitrogen compounds contained in the second of said mixtures, which process comprises: (1) contacting the first of said mixtures with a solid partially dehydrated zeolitic metalloc alumino silicate adsorbent having substantially uniform pores of at least about 7 Å. in diameter and having adsorbed thereon the organic nitrogen compounds incident to the second of said mixtures, whereby the said adsorbed organic nitrogen compounds incident to said second mixture are replaced by the organic nitrogen compounds contained in said first mixture and there is produced a first effluent comprising non-adsorbed hydrocarbon components of said first mixture and the displaced organic nitrogen compounds incident to said second mixture; (2) separating the organic nitrogen compounds 10 from said first effluent to produce a first substantially nitrogen-free hydrocarbon product; (3) contacting said second mixture with the adsorbent having adsorbed thereon the organic nitrogen compounds incident to said first mixture, whereby the said adsorbed organic nitrogen compounds contained in said first mixture are replaced by the organic nitrogen compounds contained in said second mixture and there is produced a second effluent comprising the non-adsorbed hydrocarbon components of said second mixture and the displaced organic nitrogen compounds 20 incident to said first mixture; (4) separating the organic nitrogen compounds from said second effluent to produce a second substantially nitrogen-free hydrocarbon product; and (5) continuing the alternate contacting of said adsorbent with said first and second hydrocarbon mixture.

2. A process according to claim 1 wherein the said first and second hydrocarbon mixtures are obtained by the fractionation of a single feed stream of relatively wide boiling range into a relatively low-boiling fraction and a 30 relatively high-boiling fraction.

3. A process according to claim 1 wherein, in steps (2) and (4) the said separations are effected by distillation.

4. A process according to claim 1 wherein the amounts of said first and second hydrocarbon mixtures employed in steps (1) and (3) are so proportioned relative to each other that the time required to replace the adsorbed nitrogen compounds in step (1) is substantially equal to the time required to replace the adsorbed nitrogen compounds in step (3).

5. A process according to claim 1 in combination with the step of periodically contacting the said adsorbent with an oxygen-containing gas at an elevated temperature sufficient to burn hydrocarbonaceous residues therefrom.

6. A process according to claim 1 wherein the said adsorbent is maintained in the form of a fixed compact bed, and said contacting steps are carried out by passing said first and second hydrocarbon mixtures therethrough in opposite directions.

7. A process according to claim 1 wherein steps (1) and (3) are effected in first and second contacting zones, respectively, and said adsorbent is circulated continuously and successively therethrough.

8. A process according to claim 1 wherein the diameter of the pores of said adsorbent is between about 7 Å. and 60 about 13 Å.

9. A process according to claim 2 wherein the said fractionation is so controlled that the amounts of said low-boiling and said high-boiling fractions are such that the time required to replace the adsorbed nitrogen compounds in step (1) is substantially equal to the time required to replace the adsorbed nitrogen compounds in step (3).

10. A process according to claim 4 wherein said amounts of said first and second hydrocarbon mixtures employed in steps (1) and (3) are controlled by varying the individual rates at which said mixtures are contacted with the adsorbent in said steps (1) and (3).

11. A process for denitrogenating a plurality of hydrocarbon mixtures comprising a mixture of lowest boiling range, a mixture of highest boiling range, and at 75

least one mixture of intermediate boiling range, each of said mixtures being contaminated with normally incident organic nitrogen compounds, which process comprises: (1) contacting the said mixture of lowest boiling range with a solid partially dehydrated zeolitic metallo aluminosilicate adsorbent having substantially uniform pores of at least about 7 Å. in diameter, whereby there is obtained a lowest boiling effluent containing the non-adsorbed hydrocarbon components of said lowest boiling mixture and any nitrogen compounds previously adsorbed on said adsorbent; (2) thereafter contacting the adsorbent with the mixture of next highest boiling range, whereby there is obtained an intermediate boiling effluent comprising the non-adsorbed hydrocarbon components of said mixture of next highest boiling range and organic nitrogen compounds adsorbed in the preceding contacting step; (3) repeating step (2) until all of said mixtures of intermediate boiling range have been contacted with said adsorbent; (4) contacting the adsorbent with said mixture of highest boiling range, whereby there is obtained a highest boiling effluent comprising the non-adsorbed hydrocarbon components of said highest boiling effluent and organic nitrogen compounds adsorbed in the preceding contacting step; (5) regenerating the adsorbent after said contacting with said highest boiling fraction; and (6) separating the organic nitrogen compounds from each of said effluents to produce hydrocarbon mixtures of substantially reduced nitrogen content.

12. A process according to claim 11 wherein, in step (5), said adsorbent is regenerated by contacting it with

an oxygen-containing gas at a temperature sufficient to burn hydrocarbonaceous residues therefrom.

13. A process according to claim 11 wherein the diameter of the pores of said adsorbent is between about 7 Å. and about 13 Å.

14. A process according to claim 11 wherein the said plurality of hydrocarbon mixtures is obtained by the fractional distillation of a single hydrocarbon mixture of relatively wide boiling range.

15. A process according to claim 11 wherein each of said contacting steps is effected in a separate contacting zone, and said adsorbent is circulated continuously and successively therethrough.

16. A process according to claim 11 wherein, in step (5), the said adsorbent is regenerated by contacting it with at least one of said mixtures having a boiling range below that of said highest boiling mixture.

17. A process according to claim 11 wherein the pore diameter of said adsorbent is about 13 Å.
